UNITED STATES PATENT OFFICE.

DOUGLAS E. FREEMAN, OF TAMPA, FLORIDA, ASSIGNOR OF ONE-HALF
TO CHARLES K. GRABLE, OF TAMPA, FLORIDA.

INDEX SYSTEM.

No. 821,710.

Specification of Letters Patent.

Patented May 29, 1906.

Application filed October 9, 1905. Serial No. 282,029.

To all whom it may concern:

Be it known that I, DOUGLAS E. FREEMAN, a citizen of the United States, residing at Tampa, in the county of Hillsboro and State of Florida, have invented a new and useful 5 Index System, of which the following is a specification.

This invention relates to indexing, and is particularly designed to produce an improved 10 numerical indexing system.

The present invention is particularly designed for indexing way-bills and to make use of the way-bill number as a key to the 15 page and column of a record-book in which an entry of the way-bill is kept.

With these and other objects in view the present invention consists in the combination and arrangements of parts, as will be hereinafter more fully described, shown in 20 the accompanying drawings, and particularly pointed out in the appended claims.

In the accompanying drawings, Figure 1 is a view of an index-page embodying the features of the present invention. Fig. 2 is a 25 view of a way-bill. Fig. 3 is a view of a station-expense bill. Fig. 4 is a detail view illustrating a modification. Fig. 5 is a view showing the manner of numbering the initial pages of the book.

30 In setting forth the present invention a description of one of the pages of the index will first be given, and then the manner of making the entries in connection with the way-bills and station-expense bills will be 35 explained.

Upon reference to Fig. 1 of the drawings, wherein has been shown at A one of the index-pages, it will be seen that this page is divided into a series of main columns, each 40 of which has been designated B, extending from the top to the bottom of the page, with a transverse heading-column C extending entirely across the page at the tops of the main columns. The transverse heading-column C is of course intersected and subdivided by the main longitudinal columns B, and in these subdivisions appear the numerals from "0" to "9" in their numerical succession from left to right of the page. Each 45 of the main columns is subdivided into four supplemental columns, of which the left-hand column is designed to receive the name of the place from which the way-bill

was received, and it is therefore headed "W. B. From." The next column is designed to receive the date of the way-bill and is appropriately headed "W. B. Date." The next column is designed to receive the way-bill number and is therefore headed "W. B. No.," while the next column is designed to receive the number of the station-expense bill, or what is technically known as the "Station Pro." and is therefore headed "Station Pro." Within the right-hand portion of each "W. B. No." column the page-number, which in the present illustration is "75," is printed to form a column in accordance with the number of entries the "W. B. No." column is capable of containing. Prefixed to each of the numbers "75" in each of the columns is the number of the respective column, there being a space at the left-hand side of the members of each column of numbers for the reception of an entry, as will be hereinafter described.

In making use of the present index when 75 a way-bill is received—such for instance, as illustrated at D in Fig. 2 of the drawings—an entry of the way-bill is made in the index, the location of the entry being determined by the way-bill number, which is shown at 80 E and in this instance is "L 3475." In accordance with the present method the last two digits of the way-bill number indicate the page of the index upon which the entry is to be made, which in the present instance 85 is "75," while the third from the last digit, which is "4," indicates the column in which the entry is to be made. To enter the present way-bill, the clerk turns to page 75 and makes the entry at any point in column 4 90 thereof, it of course being customary to make the entry immediately following the last entry. It is designed to have the index-page and the entry made in contrasting colors—for instance, the column of numbers 95 being printed in black and the entries made with red ink. The present entry is made by writing in the "W. B. From" column the name of the station from which the way-bill was received—for instance, Jacksonville—the 100 date of the way-bill being entered in the next column and the remaining characters of the way-bill number prefixed to the printed number "475" in alignment with the place and date entry. Either before or after the 105 way-bill has been entered in the index and

"Expense Bill" or "Station Pro." is made out according to some approved form, such as shown in F in Fig. 3 of the drawings. Upon this bill is entered the date of the receipt of the way-bill and the number and date of the way-bill. The "Expense Bill" or "Station Pro." is of course given a serial number, as shown at G, which in the present instance is "1080," and the number "1080" is entered in the "Station Pro." column.

- The present index has been designed for quickly obtaining the number of the "Expense Bill" or "Station Pro." when only the number and date of the way-bill are known.
- 15 For example, the way-bill number being "L 3475," it is merely necessary to refer to the page designated by the last two digits of the way-bill number, which is "75," and then to the column of that page which is indicated by the third from the last digit of the way-bill number, which is "4," whereupon the way-bill number may be conveniently located by looking for the characters which are prefixed to the last three digits of the way-bill number. When a way-bill number has been located, the "Expense Bill" or "Station Pro." number will be found in the next adjacent right-hand column, which in the present instance is "1080."
- 20 30 When an index-book covers a period of a year only, the date of the "Station Pro." is not entered; but where the book covers a period of more than a year it will be found useful to also enter the date of the "Station Pro." and to permit of entering the date and number of the "Station Pro." it is proposed to employ a double column, as indicated in Fig. 4 of the drawings, one half the column being provided with the heading "Date" and the other with the heading "No." By preference the date-section of the "Station Pro." column is adjacent the "Way-bill No." column in order that there may be no confusion between the "Way-bill" numbers and the "Station Pro." numbers.

45 To provide for the entry of way-bills whose three final digits include one or more naughts, the initial pages of the book are numbered, as indicated in Fig. 5—that is to say, the first page is numbered "00," the second "01," the third "02," and so on to "09," after which the pages are numbered consecutively from "10" upward. In explanation of the utility of this numbering of the pages it will be supposed that it is desired to look up a way-bill whose final digits are "00." The book is opened to the page numbered "00," and the way-bill entry will be found in the main column of this page, according to the digit that precedes the naughts of the "W. B. No." Again, to ascertain the location of a way-bill whose last three digits are "309" the book should be opened to page-number "09," and the entry will be found in the third column.

Having thus described the invention, what is claimed is—

1. An index-sheet having a sheet-number, and numbered columns of stock-figures, each column of figures being made up of the sheet-number and the column-number. 70
2. An index-sheet having a sheet-number, and numbered columns of stock-figures, each column of figures being made up of the sheet-number and the column-number prefixed thereto. 75
3. An index-sheet having a sheet-number, a series of ruled columns numbered consecutively from "0" to "9," each column having a column of stock-figures made up of the page-number and the column-number prefixed thereto. 80
4. An index-sheet having a sheet-number, and numbered columns of stock-figures, each column of figures being made up of the sheet-number and the column-number, there being a space in front of each column of figures for the entry of characters prefixed to the stock-figures. 85
5. An index-sheet having a sheet-number and a series of numbered ruled columns which are subdivided, one subdivision of each column having a column of figures made up of the sheet-number and the column-number, there being a space in front of each column of figures for the entry of characters prefixed to the stock-figures. 90
6. An index-book having its initial pages successively numbered "00," "01" and so on to "09," the succeeding pages being consecutively numbered from "10" upward, each page being divided into a series of columns numbered from "0" to "9," each column being subdivided into supplemental columns, and one supplemental column of each main column having a column of stock-figures made up of the page-number with the column-number prefixed thereto, there being a space in front of each column of figures for the entry of characters to be prefixed to the figures. 95
7. An index-sheet having a sheet-number, the sheet being divided into a plurality of main columns numbered consecutively from "0" to "9," each main column being subdivided into supplemental columns which have the respective headings "W. B. From," "W. B. Date," "W. B. No.," and "Station Pro.," the "W. B. No." column having a column of figures made up of the sheet-number with the respective main - column number prefixed thereto, there being a space in front of each column of figures for the entry of characters to be prefixed thereto. 100
8. An index-sheet having a sheet-number, the sheet being divided into a plurality of main columns numbered consecutively from "0" to "9," each main column being subdivided into supplemental columns which have the respective headings "W. B. From," "W. B. Date," "W. B. No.," and "Station Pro.," 105
9. An index-sheet having a sheet-number, the sheet being divided into a plurality of main columns numbered consecutively from "0" to "9," each main column being subdivided into supplemental columns which have the respective headings "W. B. From," "W. B. Date," "W. B. No.," and "Station Pro.," 110
10. An index-sheet having a sheet-number, the sheet being divided into a plurality of main columns numbered consecutively from "0" to "9," each main column being subdivided into supplemental columns which have the respective headings "W. B. From," "W. B. Date," "W. B. No.," and "Station Pro.," 115
11. An index-sheet having a sheet-number, the sheet being divided into a plurality of main columns numbered consecutively from "0" to "9," each main column being subdivided into supplemental columns which have the respective headings "W. B. From," "W. B. Date," "W. B. No.," and "Station Pro.," 120
12. An index-sheet having a sheet-number, the sheet being divided into a plurality of main columns numbered consecutively from "0" to "9," each main column being subdivided into supplemental columns which have the respective headings "W. B. From," "W. B. Date," "W. B. No.," and "Station Pro.," 125
13. An index-sheet having a sheet-number, the sheet being divided into a plurality of main columns numbered consecutively from "0" to "9," each main column being subdivided into supplemental columns which have the respective headings "W. B. From," "W. B. Date," "W. B. No.," and "Station Pro.," 130

the "W. B. No." column having a column of figures made up of the sheet-number with the respective main-column number prefixed thereto, there being a space in front of each 5 column of figures for the entry of characters to be prefixed thereto, the "Station Pro." column being divided into two columns which are respectively headed "Date" and "No."

9. An index-sheet having a sheet-number 10 and a series of numbered main columns, each main column being subdivided into supplemental columns, one of the supplemental columns being subdivided and its subdivisions respectively headed "Date" and "No." the

adjacent supplemental column being provided with a column of stock-figures made up of the sheet-number to which is prefixed the main-column number, there being a space in front of the column of figures for the entry of characters to be prefixed thereto.

15 In testimony that I claim the foregoing as my own I have hereto affixed my signature in the presence of two witnesses.

DOUGLAS E. FREEMAN.
